UNITED STATES PATENT OFFICE

JOHN D. PEARMAIN, OF SCARBOROUGH, NEW YORK

ILLUMINATED SIGN

Application filed September 21, 1928. Serial No. 307,506.

My invention relates to illuminated signs of the type in which daylight first passes through a horizontally disposed stencil plate to a reflecting surface, and then from this surface to the eye of the observer, or from an inclined mirror through a stencil, customarily called "day light" signs. The sign is rendered more brilliant by the reflection of the, usually colored, stencil in the reflector of a 10 darkened chamber.

Such signs are operable only in the day time, or by artificial light above the structure.

The object of my invention is to improve such signs by enabling the sign to be reflected and read not only in the day time but also at night, when artificial light falls from some distant source on the sign, either from one direction or from different directions, as from a shop window, street lamp, or motor vehicle headlights, thus eliminating the necessity of incorporating a separate source of light in the sign.

My invention consists of an attachment to this end.

Referring to the drawings, in which like parts are similarly designated—

Figure 1 is a perspective view of one form of my invention.

Fig. 2 is a cross-section thereof.

Fig. 3 shows a construction having two auxiliary reflectors.

Fig. 4 shows the use of a concave auxiliary reflector.

Fig. 5 shows another modification, where in the auxiliary reflector is hinged, and also pivoted to swing horizontally.

Fig. 6 is a further modification, for hanging in front of or in a store window.

Fig. 7 is a modification showing the use of clear glass reflectors.

My attachment is shown as applied to a casing *a* having a stencil plate *b*, usually covered by a sheet of glass, and an inclined reflector or mirror *c*.

This much of the structure is well known, but the stencil plate is generally arranged at the top, as in Figs. 1-4. So far as I am aware, the stencil plate has not been arranged at the bottom, as in Fig. 6.

In such known structures daylight passes

through the upper, horizontally disposed stencil plate *b* and reflects the image of the stencil in the reflector or mirror *c*, so that the stencil shows with greater brilliancy. Such signs are only used in daylight. 55

My improvement is constructed so as to make such signs operable at night time also, the light for illuminating them being derived from a distant source, such as street lamps, vehicle headlights, store windows and the like. 60

To a structure such as above described I apply an open frame 7 resting on the sign structure, two opposite sides of which are provided with slots 8 through which pass bolts 9 provided with thumb-nuts 10, or equivalent fastening means. Mounted on frame 7 by means of hinges 11 is an auxiliary frame 12 for holding an auxiliary reflector 13. 70

The auxiliary reflector frame 12 is provided with lugs 14 to which a slotted rod 15 is connected. A bolt 16 passes through the slot and is provided with a thumb-nut 17, whereby the angularity of the auxiliary frame may be adjusted with respect to the stencil plate *b*. The auxiliary reflector may be a sheet of clear glass, or a metallic or glass mirror. 75

The structure shown in Figs. 1 and 2 when placed upon a motor vehicle top will operate in daylight, as usual, and at night by light directed from headlights, street lamps, &c. at the rear against the auxiliary reflector 13, that deflects the rays down through the stencil onto the mirror *c* to be viewed from the front. 80

The frame 7 is adjustable from front to rear by reason of the slots 8, bolts 9 and nuts 10. The frame may also be readily removed and reversed, so that the auxiliary reflector 13 will be directed toward the front. 85

In Fig. 3 the frame 7 is shown as provided with two auxiliary frames 12 and 12^a mounted at opposite sides of the frame 7 and provided with mirrors or reflectors. One of these auxiliary frames, 12^a, is adjustable as to angle, as in Fig. 1, and one of the reflectors, say that in frame 12, is preferably arranged above the other and is also adjustable, for 90 95 100

both height and angle by slotted rods 15^a and 15^b. This arrangement permits light from a distant source from either or both directions to illumine the sign. The reflector 12 may be so adjusted that instead of reflecting directly through the stencil plate, it will direct light by double reflection through the plate, i. e., first to mirror in frame 12^a and then through the plate. In this instance the sign will be seen upright in mirror in frame 12, as well as in mirror c.

In Fig. 4 the frame 7 is provided with a concave reflector 19. A reverse image will also be seen in the reflector 19.

In Fig. 5 the case a is provided with a lateral flange 20, on which rests a plate 21 that is rotatably fixed to the flange 20 by a bolt or pin 22.

The plate and flange are provided with registering holes through which a bolt 23 passes. The bolt is provided with a nut 24 and holds the plate 21 in any desired rotated position with respect to pin 22.

Hinges 25 connect the auxiliary reflector frame 26 to the plate 21. Brackets 27 are mounted on the plate 21 and are provided with slots 28 through which pass screws 29 provided with thumb-nuts 30 for holding the frame 26 in angular relation to stencil plate b. In this case the frame 26 is hinged at the side of the casing, and the reflector therein receives light from lights at the street curb or shop windows, &c.

In Fig. 6 I have shown the case a inverted for hanging at the front of or within a shop window by chains or cords 31 engaged by hooks 32 or the equivalent, on the casing a. Suspended from hooks 33 by chains 34 is a frame 35 carrying a reflector 35, preferably cylindrical, to the sides of which frame are hinged auxiliary reflectors 36 adjustably supported at the proper angle by slotted arcs 37, as in Fig. 5. The frame 35 is itself adjustable to and from the casing a as well as angularly, by engaging the hooks 33 in any one of the links of the chains 34.

Figure 7 shows two sheets 40 of transparent glass arranged at an angle to one another and closed at the sides, if desired, by a transparent sheet of glass 41, so, as, in effect, to form a prism that effectually keeps out rain and dust. This arrangement will direct light from any direction onto the stencil plate.

It is obvious that reflectors like 36 may be mounted on all four sides of the frame 35 instead of on only two sides.

The top lights of a show-window, or daylight shines on the auxiliary reflectors 35^a and 36 that direct the light through the stencil onto the mirror c.

I claim—

1. An illuminated sign having a stencil plate through which the daylight passes, and a reflector on one side of the plate into which the stencil is projected and in which

the image of the stencil is projected and viewed; in combination with a plurality of auxiliary reflectors at different angles arranged on the opposite side of said plate to reflect artificial light from distant different sources through the plate to the first reflector normally unassociated with the sign.

2. The combination with a sign having a stencil plate and an associated reflector; of a plurality of auxiliary reflectors arranged to reflect artificial light from a distant source through the plate to its associated reflector, and means to adjust the auxiliary reflectors relatively to the plate.

3. An illuminated sign having a stencil plate through which daylight passes and a reflector into which the stencil is reflected and in which it is viewed; in combination with an auxiliary reflector on the opposite face of the plate, means to adjust the relative position of the auxiliary reflector to the plate; and means to adjust the angularity of the auxiliary reflector.

4. An illuminated sign having a stencil plate through which daylight passes, and a reflector in which the image of the stencil is viewed; in combination with a plurality of auxiliary reflectors on the opposite side of the plate arranged to reflect artificial light from different directions through the plate to the first reflector.

5. An illuminated sign having a stencil plate through which daylight passes, and a reflector in which the image of the stencil is viewed; in combination with a plurality of auxiliary reflectors on the opposite side of the plate arranged to reflect artificial light from different directions through the plate to the first reflector, means to bodily shift the auxiliary reflectors relatively to the plate and means to adjust the angularity of the auxiliary reflectors one to the other and to the plate.

6. An illuminated sign having a rectangular stencil plate, and an inclined mirror associated therewith; in combination with a frame slidable above and at opposite sides of the sign, auxiliary reflectors hinged at opposite sides of the frame, rods pivotally connected to the reflectors and means to secure the rods in adjusted position to regulate the angular relation of the reflector to the frame and plate, said reflectors arranged to be illuminated by a distant source of artificial light and reflect the stencil in said mirror during the night.

7. An illuminated sign having a stencil plate and an inclined mirror cooperating therewith; in combination with an auxiliary reflector above the plate, and means for permitting adjustment of the auxiliary reflector in angular relation to the plate and as to height with respect to the plate.

8. An attachment for "daylight signs" comprising a frame for attachment to the

sign, an auxiliary inclined mirror mounted on the frame, and arranged to reflect light to said sign, that ordinarily does not illuminate the sign, and means for securing the frame to said sign for reversal of the auxiliary mirror with respect to the sign.

5 9. An attachment for "daylight signs" comprising a frame for attachment to said sign, an auxiliary mirror on the frame, and means for varying the angularity of the mirror to the frame and sign.

10 10. An attachment for "daylight signs" comprising a frame for mounting on the sign, a mirror angularly mounted at one side of the frame, a second mirror mounted on the opposite side of the frame above the first mirror and adjustable as to height.

15 11. An attachment for "daylight signs" comprising a frame for mounting on the sign, a mirror angularly mounted at one side of the frame, a second mirror mounted on the opposite side of the frame above the first mirror and adjustable to height, and means to adjust the angularity of both mirrors.

20 25 In testimony that I claim the foregoing as my invention, I have signed my name here-to.

JOHN D. PEARMAIN.
